UNITED STATES PATENT OFFICE

EARL H. ROLLINSON, OF IRVINGTON, NEW JERSEY

DESIGN FOR A THERMOSTATIC ALARM

Application filed December 8, 1930. Serial No. 37,916. Term of patent 3½ years.

To all whom it may concern:

Be it known that I, EARL H. ROLLINSON, a citizen of the United States, residing at Irvington, in the county of Essex and State of New Jersey, have invented a new, original, and ornamental Design for a Thermostatic Alarm, of which the following is a specification, reference being had to the accompanying drawing, forming part thereof.

Figure 1 is a top plan view of a thermostatic alarm showing my new design.

Figure 2 is a side elevational view of the same.

Figure 3 is a bottom plan view thereof.

I claim:

The ornamental design for a thermostatic alarm, as shown.

EARL H. ROLLINSON.
